UNITED STATES PATENT OFFICE.

WILBERFORCE BEECHER HAMMOND, OF BOSTON, MASSACHUSETTS, ASSIGNOR, BY
MESNE ASSIGNMENTS, TO COMBINED HEAT AND SPRINKLER COMPANY, A COR-
PORATION OF MASSACHUSETTS.

AUTOMATIC SPRINKLER.

1,233,777.

Specification of Letters Patent. Patented July 17, 1917.

Application filed January 28, 1915. Serial No. 4,934.

To all whom it may concern:

Be it known that I, WILBERFORCE BEECHER HAMMOND, a citizen of the United States, and resident of Boston, in the county of 5 Suffolk and State of Massachusetts, have invented new and useful Improvements in Automatic Sprinklers, of which the following is a specification.

My invention relates to automatic sprinklers for protection against fire, and has for its object the production of a sprinkler head which may be immediately secured to a hot water pipe but nevertheless maintain by reason of its principles of construction the 10 sensitive fusible member at a safely low temperature, so that, although the sprinkler head itself is intimately secured to a circulation pipe which may contain water at a temperature as high as 230° F. or even 15 higher, the heat sensitive fusible member which is a characteristic of all commercially acceptable sprinkler heads, will nevertheless remain at a temperature far below that at which it is designed to soften and release 20 the sprinkler in case of accidental fire.

My improvements are adapted and applicable to that type of sprinkler (of which there are several examples in use) in which the valve which closes the sprinkler aperture is held in closed position by means of bars or levers under a bending strain. According to the particulars of construction of the example of such type of sprinkler head which may be selected, there may be 30 one or more of such bar or lever members under bending strain. For illustration of my invention I have taken two examples of 35 sprinklers of the type above designated, and it will be perceived from the following description that my invention is applicable to 40 any sprinkler of this type.

In the drawings hereto annexed,—

Figure 1 shows a sprinkler head of the above designated type known commercially 45 as the Evans sprinkler, modified, however, by the application thereto of my invention;

Fig. 2 shows a sprinkler head of the commercially known Walworth type, similarly altered and qualified by the addition of my 50 invention; and

Fig. 3 shows, in section, a modified form of the lever arm of the type of sprinkler illustrated in Fig. 1.

Referring to Fig. 1, which illustrates my

invention as applied to a sprinkler of the 55 Evans type (see U. S. Patent No. 729,306): The sprinkler head S is attached to a pipe connection R which in the case proposed forms the part of a hot water circulating system. The valve V of the sprinkler is held 60 firmly pressed to its seat under normal conditions by means of the toggle members T', T², which are held in position by means of lever arms, which in the illustration shown are constructed according to my invention. 65 These lever arms as heretofore embodied in sprinklers of the Evans type and shown in said Patent No. 729,306 are simply integral metal extensions from the toggle members T', T², themselves, and these extensions are 70 held under bending strain by means of a fusible link F which serves as a tie between the two arms. In the standard Evans sprinkler, however, these two arms are relatively quite large bodies of metal highly conductive of heat, so that if, as is usually the case, the fusible link F is of such composition that it will soften and let go its hold 75 upon the arm when raised to a temperature of about 160° F., and such a sprinkler head 80 were to be placed in close junction with a hot water heating pipe (in which the water occasionally has to be heated as high as 230° F.) the fusible member might become hot enough to release the sprinkler valve. 85

In order to conserve the mechanical utilities of the lever arms and at the same time to deprive them of their capacity for conducting heat, I construct them in the manner following which will be understood by reference to Fig. 1.

By means of perforations in toggle members T', T², I mount thereon slender rods L, L², preferably of steel, or it may be of a high quality of bronze, and inclose these 95 rods with a stout sleeve of insulating material, such as for instance, "asbestos wood". These sleeves I, I², are perforated so that they fit over the slender rods L, L². By means of nuts N', N², and W', W², at the 100 inner and outer ends of rods L, L², respectively, I then set the composite lever arms tightly against the toggle members T', T², respectively. The outer ends of the sleeves I', I², of heat insulating material, enter the 105 holes F', F², in the link F in the usual manner. The link F comprises some readily fusible material, and performs the office of

the heat-sensitive member which in emergency releases the sprinkler.

The bending strain placed upon these composite lever arms produces a condition of compression in the lower side of the insulating sleeve I' and the upper side of the insulating sleeve I^2 , while the tension produced in the rods L , L^2 , initially, by means of the nuts N' , W' , N^2 , W^2 , and finally by 10 the strut action of the insulating sleeves assists the sleeves of insulating material I' , I^2 , in sustaining the tensile stress on their outer sides, which otherwise such insulating material would be ill-qualified to endure. 15 For the most part, however, the high capacity of such material for resisting compressive strains is depended on to sustain the various parts of the valve-holding system in their proper relation.

20 Now it will be observed that the only channels for the ready conduction of heat from the toggle members T' , T^2 , to the fusible link F , are the slender metal rods L , L^2 , through which a negligible quantity of heat 25 can be transmitted on account of the small cross section of these members. It will be observed, also, that the heat conductive members of this system need not and in the instance shown do not make any contact with 30 the fusible link F which is, on the contrary, in contact with the heat-insulating members I' , I^2 .

The metal members L , L^2 , though large enough to supply all the tensile strength 35 necessary, are too small to transmit heat to any material extent, whereas the members I' , I^2 , which provide the compressive strength necessary to resist bending quite 40 completely resist the transmission of heat through their substance. As thus constructed the sprinkler of the type designated is of ample strength to maintain its normal condition of valve closure, but is nevertheless so 45 highly resistant to the transmission of heat that the fusible member is unaffected by heat conducted through the pipe R even though the temperature therein be very high.

A modified form of compressible lever arm is shown in section in Fig. 3. Here the 50 toggle member T' is provided with a headed stud T^3 , over which the heat-insulating material I' is molded. Slender bars or wires I^3 of high tensile strength are embedded in the said insulating material, and lend to it the 55 necessary capacity to resist bending strain. The link receiving groove F' is formed in the outer end of the insulating member I' .

To indicate by way of further example 60 how this invention may be embodied in other examples of sprinkler heads of the same general type, I have shown in Fig. 2 a sprinkler of another type commercially known as the Walworth (see U. S. Patent No. 467,970), in which the valve V is held 65 to its seat by means of a bell-crank lever

pivoted at P , the shorter arm A' of the lever bearing upon the top of the valve, and the longer arm being tied to the top of the sprinkler attachment by means of a fusible link T . As heretofore constructed the longer 70 upwardly extending arm of the bell-crank lever in the Walworth structure is made of metal sufficiently stout to sustain the bending strain incident to holding the valve V to its seat, and is therefore a member admirably adapted to transmit heat by conduction to the fusible link T . 75

My invention as applied to the Walworth sprinkler may be carried out as follows: The upwardly extending metal portion of 80 the bell-crank lever at A is made of reduced cross section, a cross section preferably so small that no appreciable amount of heat will be conducted through it. A seat A^2 is formed at the base of the slender arm 85 A and over this arm there is placed a sleeve of heat-insulating material B , this being held tightly in place and under compression by means of a nut M at the upper end of the rod or slender extension A . The fusible link T bears on the heat-insulating sleeve B and ties the composite lever arm to the upper projection O of the sprinkler. It will not be necessary further to describe this 90 application of my invention since it will be 95 obvious that the same conditions inhere therein as characterize the form of my invention shown in Fig. 1. The type of 100 sprinkler illustrated in Fig. 2 does not lend itself so readily to the application of my invention as that shown in Fig. 1, since one of the conductive paths for heat (from the valve V to the upper projection O) remains substantially the same as in the commercially known Walworth sprinkler; the provision of the slender arm A and heat insulating strut B removes one of the heat conductive paths previously existing in this 105 type, and to that extent reduces the liability of the fusible member T to unintended 110 fusion, should such a sprinkler be associated with a hot water pipe.

Generally speaking, my invention is characterized by the employment of insulating material, in a sprinkler structure of the type 115 designated, which intervenes between the sensitive fusible link and metallic parts of the sprinkler through which heat may be transmitted by conduction from the pipe on which the sprinkler is mounted, so that the fusible link or equivalent sensitive member is indifferent to heat conditions inside 120 the water-containing system, while exposed freely to heat conditions outside the said water-containing system.

More specifically, my invention is characterized by the application to that type of 125 sprinkler in which the valve is held in its seat by means of bending strain applied to a lever or bar, of a composite arm composed 130

partly of material of high tensile strength, such as metal, and partly of material of low tensile strength, but of high compressive strength and high heat insulating properties 5 and utilizing the tensile strength of the former (as a tie) and the compressive strength of the latter (as a strut) to sustain the bending strain necessary to hold the sprinkler valve in its normal closed position, 10 and by thus minimizing the amount of heat which can be conducted from the parts of the sprinkler head in immediate juxtaposition to the valve to the fusible retaining member which normally holds the bar or 15 lever member under bending strain to keep the valve closed.

I claim:

1. In an automatic sprinkler of the type designated, the combination with a retaining piece comprising readily fusible material, of valve-restraining means comprising an arm held under bending strain by said retaining piece, said arm comprising a tension-member of metal and a strut member 25 of heat insulating material.

2. In an automatic sprinkler of the type designated, the combination with a retaining piece comprising readily fusible material, of valve-restraining means comprising 30 an arm held under bending strain by said retaining piece, said arm comprising a ten-

sion-member of metal and a strut member of heat insulating material, the retaining piece being in contact with the strut member.

35

3. In an automatic sprinkler of the type designated, the combination with a retaining piece comprising readily fusible material, of valve-restraining means comprising an arm held under bending strain by said 40 retaining piece, said arm comprising a relatively slender metallic tension member and a sleeve of heat insulating material surrounding said tension member and constituting a strut member.

45

4. In an automatic sprinkler of the type designated, the combination with a retaining piece comprising readily fusible material, of valve-restraining means comprising 50 an arm held under bending strain by said retaining piece, said arm comprising a relatively slender metallic tension member and a sleeve of heat insulating material surrounding said tension member and constituting a strut member, the retaining piece being 55 in contact with the said insulating sleeve.

Signed by me at Boston, Massachusetts, this 20th day of January, 1915.

WILBERFORCE BEECHER HAMMOND.
